Primary Examiner — Richard E Chilcot

(57) **CLAIM**

The ornamental design for water sports apparatus, as shown and described.

DESCRIPTION

The patent or application file contains at least one drawing executed in color. Copies of this patent or patent application publication with color drawing(s) will be provided by the Office upon request and payment of the necessary fee.

1. Water sports apparatus

1.1 Perspective;

1.2 Front;

1.3 Top;

1.4 Side, the opposite side being a mirror image.

The "RedShark" forming part of the claimed design is a registered trademark of RED SHARK EUROPE, S.L.

1 Claim, 4 Drawing Sheets**(4 of 4 Drawing Sheet(s) Filed in Color)**(56)
